UNITED STATES PATENT OFFICE.

WILLIAM H. COLCLOUGH, OF EAST LIVERPOOL, OHIO.

SCRAPER ATTACHMENT FOR SHOVELS.

No. 844,002.

Specification of Letters Patent.

Patented Feb. 12, 1907.

Application filed November 27, 1906. Serial No. 345,330.

To all whom it may concern:

Be it known that I, WILLIAM HERBERT COLCLOUGH, a resident of East Liverpool, in the county of Columbiana and State of Ohio, have invented certain new and useful Improvements in Scraper Attachment for Shovels; and I do hereby declare the following to be a full, clear, and exact description of the invention, such as will enable others skilled in the art to which it appertains to make and use the same.

My invention relates to an improved scraper attachment for shovels, the object of the invention being to provide an improved scraper-holder fixed to the handle of the shovel to support the scraper at all times in easy reach of the operator and which will firmly hold the scraper, preventing liability of its loss.

With this and other objects in view the invention consists in certain novel features of construction and combinations and arrangements of parts, as will be more fully herein-after described, and pointed out in the claims.

In the accompanying drawings, Figure 1 is a view in elevation showing the scraper in the holder. Fig. 2 is a view of the holder with scraper removed, and Fig. 3 is a view in section.

1 represents a shovel-handle, to the flat portion 2 of which adjacent to the handheld 3 my improved scraper-holder 4 is secured. The holder 4 comprises a sheet-metal blank 35 bent forming side flanges 5 and an upwardly-projecting longitudinal spring-tongue 6.

7 represents a shovel-scraper comprising a flat plate of sheet metal having a curved tongue 8 at its upper end to afford a ready finger-hold.

The holder 4 is perforated to receive nails or tacks to secure it to the handle and may be of the general V shape shown, or may be of other shapes desired, and the tongue 6 is provided with an inwardly-pressed lug 9 to engage behind a similar lug 10 on the scraper to more firmly hold the latter in position.

The scraper is moved down behind tongue 6 and behind the side flanges 5, the tongue 6 serving to prevent longitudinal movement of the scraper and the flanges 5 preventing lateral movement thereof. The scraper will therefore be firmly held against possibility of being jarred loose and lost and is always in convenient position for use when desired. 55

Slight changes might be made in the general form and arrangement of the parts described without departing from my invention, and hence I do not restrict myself to the precise details set forth, but consider myself at liberty to make such slight changes and alterations as fairly fall within the spirit and scope of my invention.

Having fully described my invention, what I claim as new, and desire to secure by Letters Patent, is—

1. A holder for a scraper, comprising a plate provided at one edge with a tongue lying approximately parallel to the plate, said plate provided at opposite edges with flanges, said flanges being disposed at opposite sides of the tongue.

2. A holder for a scraper, comprising a plate provided at its side edges with flanges to receive a scraper between them, said plate provided with a tongue projecting upwardly from its lower edge and disposed in front of the plate between the side flanges thereof. 75

3. The combination with a shovel-handle, of a scraper-holder secured to the flat portion of the handle and comprising a back plate having side flanges and an upwardly-projecting spring-tongue, a scraper comprising a flat blade to be moved beneath the tongue and side flanges, a finger-hold on the scraper, and a lug on the tongue to engage over a lug on the scraper-blade. 85

In testimony whereof I have signed this specification in the presence of two subscribing witnesses.

W. H. COLCLOUGH.
